UNITED STATES PATENT OFFICE.

JAMES LOGAN FITTS, OF MERCHANTVILLE, NEW JERSEY, ASSIGNOR TO WARREN WEBSTER & COMPANY, A CORPORATION OF NEW JERSEY.

VALVE.

939,823.

Specification of Letters Patent.

Patented Nov. 9, 1909.

Application filed July 10, 1909. Serial No. 506,822.

To all whom it may concern:

Be it known that I, JAMES LOGAN FITTS, a citizen of the United States, and a resident of Merchantville, Pensauken township, and 5 State of New Jersey, have invented an Improvement in Valves, of which the following is a specification.

My invention has reference to valves and consists of certain improvements which are 10 fully set forth in the following specification and shown in the accompanying drawings which form a part thereof.

The object of my invention is to provide a simple construction of valve especially 15 adapted as a modulation valve for use in steam heating systems and more especially for controlling the supply of steam to the radiator thereof, whereby predetermined amounts of steam may be admitted to the 20 radiator to suit the particular heating requirements thereof.

My object is to provide an inexpensive construction of the working parts which will maintain their operative conditions, be 25 cheaply made, and easily repaired.

My invention consists of certain details of construction constituting the operative structure of the valve and which are fully described hereinafter and more particularly 30 defined in the claims. These improvements will be better understood by reference to the drawings in which:

Figure 1 is a plan view of a valve embodying my invention; Fig. 2 is a vertical 35 sectional view of the same; Fig. 3 is a transverse sectional view through the body of the valve; Fig. 4 is a sectional elevation of the valve piece removed; Fig. 5 is a plan view of the same; and Fig. 6 is a cross section of 40 the valve piece on line $x-x$ of Fig. 4.

2, is a valve body and has an inlet 4 and an outlet 3. The valve body furthermore is provided with a conical valve seat 5 arranged within it and having its largest end 45 opening downward into the inlet port 4.

The outlet 3 communicates with the interior of the valve seat 5 by a port 8. The body is also provided with transverse walls 7 which shut off a communication between 50 the outlet 3 and the interior chamber 6 of the valve body, except by way of the port 8 in the valve seat.

10 is a conical valve plug and has a taper with the smallest diameter next to the stem

11. The conical valve piece 10 seats upon 55 the conical valve seat 5 and the stem 11 extends upward through the upper part of the valve body. A steam tight joint is made around the valve stem by a stuffing box 12 containing packing under compression by 60 means of a bushing 13.

The valve piece 10 is held upward in its seat by means of an adjustable bushing 18 which is screwed into the body below the valve seat, as indicated at 9. This bushing 65 18 is preferably a split spring ring and is of larger diameter than the largest end of the valve piece and is of smaller diameter than the inlet port 4. By adjusting the bushing 18, the valve piece is held as tightly in the 70 valve seat as is necessary to secure a tight joint.

The top of the valve stem 11 is made square to receive a handle plate 14 having a crank handle 15 and a pointer 16. The 75 plate 14 is made inverted cup shaped so as to extend over and hide the stuffing box structure through which the shaft 11 extends. This plate 14 is made circular as shown in Fig. 1 and is of less diameter than 80 the circular indicator plate or flange 19 arranged immediately below the same and formed integral with the body 2 of the valve. This indicator plate 19 contains two limit stops 17, one adjacent to the word "Open" 85 and the other adjacent to the word "Shut" and also contains numbers indicating different portions of opening. When the handle is rotated so that the pointer 16 rests against the stop 17 adjacent to the word "Shut" the valve will be completely closed 90 and when turned so that the pointer 16 rests against the stop 17 adjacent to the word "Open" then the valve is fully open. When the pointer assumes intermediate positions, 95 corresponding to the numerous places indicated upon the indicator flange 19, the valve will be opened to different degrees.

The structure of the valve is such that with less than one revolution of the handle 100 and valve piece the valve will pass from the closed condition to the full open condition and all intermediate conditions, so that the operator may know in a moment the extent of the opening.

The valve piece 10 has its face provided with a plurality of openings arranged about its circumference as indicated in Figs. 5 105

and 6. These openings vary in area and the diameter of the opening 20 is approximately twice the diameter of the opening 21, the diameter of the opening 21 is approximately 5 twice the diameter of the opening 22, and the diameter of the opening 22 is approximately twice the diameter of the opening 23. It will be seen that the turning of the valve piece brings in line with the port 8 10 these different ports or openings 20 to 23 in succession and moreover, the opening 8 is such as to width that as one of the ports is being shut off, the next adjacent port is being opened, so that at times two of these 15 ports 20 to 23 are partly opened through the port 8. This structure is such, that there is a gradual increasing steam passage area from the smallest opening to the largest and hence, the possibility of gradual adjustment 20 in the steam supply. However, in the normal operation of the valve, the positions of the valve when ordinarily adjusted and left would be to bring one of the ports 20 to 23 in line with the opening 8.

25 The angle of the taper of the plug valve 10 is such that it will not jam fast, even at considerably high pressure. The split ring or bushing 18 holds the valve piece from dropping downward and becoming lost when 30 the handle plate is removed and repacking the stuffing box about the stem is being done. By making the bushing 18 in the form of a split ring it will firmly hold itself in its adjusted position.

35 It will also be observed that in particular valve structure shown, the chamber 6 is practically sealed both to the inlet and outlet ports and consequently, there is no pressure within this chamber to produce leakage 40 through the packed joint and therefore, only a smaller amount of packing would be necessary and the packing would, moreover, have an increased life over what would be the case if the steam had free access to the stuffing 45 box.

While the construction shown is in the form which I have found excellently adapted to the commercial use of my invention, the details thereof may be modified without departing from the spirit of the invention.

Having now described my invention what I claim as new and desire to secure by Letters Patent is:

1. In a valve, the combination of the body 55 part having inlet and outlet ports and a conical valve seat within the body having its larger end in communication with the inlet port and its side in communication with the outlet port, with a conical plug valve piece 60 fitting the valve seat and having a port opening through the side and larger end and said plug valve piece also having a stem extending through the valve body, a stuffing box around the valve stem, a handle to operate the conical plug valve piece, and a ring

shaped bushing screwed into the body part below the valve piece for holding it in its valve seat with the proper degree of pressure.

2. In a valve, the combination of the body 70 part having inlet and outlet ports and a conical valve seat within the body having its larger end in communication with the inlet port and its side in communication with the outlet port, with a conical plug valve piece 75 fitting the valve seat and having a plurality of ports of relatively different sized openings through the conical face of the valve plug and at intervals about its circumference and a port through its larger end and said plug valve piece also having a stem extending 80 through the valve body, a stuffing box around the valve stem, a handle to operate the conical plug valve piece, a ring shaped bushing screwed into the body part below 85 the valve piece for holding it in its valve seat with the proper degree of pressure, and means to indicate from the outside of the valve the position of the several ports of the plug valve piece with respect to the port 90 through the valve seat.

3. In a valve, the combination of the body 95 part having inlet and outlet ports and a conical valve seat within the body having its larger end in communication with the inlet port and its side in communication with the outlet port, with a conical plug valve piece fitting the valve seat and having a port opening through the side and larger end and said plug valve piece also having a stem extending 100 through the valve body and its annular larger end extending slightly below the valve seat, a stuffing box around the valve stem, a handle to operate the conical plug valve piece, and a ring shaped bushing 105 screwed into the body part below the valve piece of larger diameter than the bottom of the valve seat and of smaller diameter than the inlet port and forming an annular abutment for holding it in its valve seat with the 110 proper degree of pressure.

4. In a valve the combination of the body part having inlet and outlet ports and a conical valve seat within the body having its larger end in communication with the inlet 115 port and its side in communication with the outlet port and also having walls for forming a closed compartment adjacent to the smaller end of the valve seat, with a conical plug valve piece fitting the valve seat and having a port opening through the side and larger end and said plug valve piece also having a stem extending through the valve body, said valve stem passing through the closed chamber to the outside of the valve 120 body, a stuffing box around the valve stem and separated from the inlet and outlet ports by the interposition of the closed chamber, a handle to operate the conical plug valve 125 piece, and a ring shaped bushing screwed 130

into the body part below the valve piece for holding it in its valve seat with the proper degree of pressure.

5. In a valve, a body having inlet and outlet ports and an annular valve seat between them, the large end of the seat opening toward one of the ports and the wall of the seat opening into another of the ports by a passageway and also having a closed chamber in communication with the small end of the conical seat but having no direct communication with the inlet and outlet ports, combined with a plug valve fitting the valve seat and provided with a port extending through its side and larger end and a valve stem extending through the closed chamber and valve body to the outside thereof, and a stuffing box carried by the valve body and forming a steam tight packing about the valve stem.

6. In a valve, a body having inlet and outlet ports and an annular valve seat between them, the large end of the seat opening toward one of the ports and the wall of the seat opening into another of the ports by a passageway and also having a closed chamber in communication with the small end of the conical seat but having no direct communication with the inlet and outlet ports,

25 30 combined with a plug valve fitting the valve seat and provided with a port extending through its side and larger end and a valve stem extending through the closed chamber and valve body to the outside thereof, a stuffing box carried by the valve body and forming a steam tight packing about the valve stem, and a handle operating device for rotating the valve stem and its plug valve having means for shielding the stuffing box.

35

40 7. In a valve, a body having inlet and outlet ports and an annular valve seat between them, the large end of the seat opening toward one of the ports and the wall of the seat opening into another of the ports
45 by a passageway and also having a closed chamber in communication with the small end of the conical seat but having no direct communication with the inlet and outlet ports, combined with a plug valve fitting the
50 valve seat and having a plurality of ports of different areas communicating in a common passage through the large end of the plug valve and opening through the conical surface thereof in relatively different positions about its circumference and a valve stem extending through the closed chamber and valve body to the outside thereof, a stuffing box carried by the valve body and forming a steam tight packing about the
55 60 valve stem, and means for limiting the rotation of the valve stem within one revolution.

tion and indicating the position of the several ports of the valve plug with respect to the passageway through the side of the valve seat.

8. In a valve, a body having inlet and outlet ports and an annular valve seat between them, the large end of the seat opening toward one of the ports and the wall of the seat opening into another of the ports by a passageway and also having a closed chamber in communication with the small end of the conical seat but having no direct communication with the inlet and outlet ports, combined with a plug valve fitting the valve seat and provided with a port extending through its side and larger end and a valve stem extending through the closed chamber and valve body to the outside thereof, a stuffing box carried by the valve body and forming a steam tight packing about the valve stem, a handle operating device for rotating the valve stem and its plug having means for shielding the stuffing box, and a ring bushing adjustably secured in the valve body below the large end of the plug valve for holding it in position within its seat.

9. In a valve, a body having inlet and outlet ports and an annular valve seat between them, the large end of the seat opening 90 toward one of the ports and the wall of the seat opening into another of the ports by a passageway and also having a closed chamber in communication with the small end of the conical seat but having no direct 95 communication with the inlet and outlet ports, combined with a plug valve fitting the valve seat and provided with a port extending through its side and larger end and a valve stem extending through the closed 100 chamber and valve body to the outside thereof, a stuffing box carried by the valve body and forming a steam tight packing about the valve stem, a handle operating device for rotating the valve stem and its plug valve 105 having means for shielding the stuffing box, and a ring bushing adjustably secured in the valve body below the large end of the plug valve for holding it in position within its seat consisting of a split ring having the 110 upper surface in annular form to work against the valve plug and the lower part screw-threaded to form an adjustable connection with the valve body below the large end of the conical seat. 115

In testimony of which invention, I hereunto set my hand.

JAMES LOGAN FITTS.
